CLOSURE FASTENER DEVICE

Henry D. Sneider, Brooklyn, N. Y.

Application October 22, 1936, Serial No. 107,070

5 Claims. (Cl. 24—207)

The present invention relates to closure fastener devices of the type used in connection with a pair of flexible body members having beaded edges for opening and closing the same by sliding connection.

In usual devices of this nature which have come to my attention, the fastening clips are so formed and constructed as to cause a wedging or binding action as they are slid along the beaded edges when it is desired to open and close the container or article of clothing. Due to this wedging and binding action the fastening clips do not only jam during the operation, but frequently become displaced from their guiding and supporting beaded edges.

One of the primary objects of my present invention resides in the construction of a unitary piece of comparatively thin metal which is formed in such a novel manner as to provide a pair of oppositely disposed and elongated bead-receiving passages, which, when completely formed will remain in its folded position.

A further object of the invention resides in the formation of a pair of elongated beaded edges in connection with the metallic clips having elongated openings in which a slight space is formed therebetween to prevent the displacement or accidental separation of the metallic clips from their beaded edges, at the same time permitting an extremely free sliding movement therebetween without the slightest possibility of binding or wedging.

A still further object of the present invention resides in the novel construction of the metallic fastening devices which permits their manufacture from a comparatively narrow strip or band of metal with the minimum amount of waste and which lends itself to manufacture on a high production basis.

Other objects of this invention will herein-after be set forth, or will be apparent from the description and the drawing, in which are illustrated embodiments for carrying out the invention.

The invention, however, is not intended to be restricted to any particular construction or arrangement of parts, or to any particular application of such construction, or to any specific manner of use, or to any of the various details thereof, herein shown and described, as the same may be modified in various particulars or be applied in many varied relations without departing from the spirit and scope of the claimed invention, the practical embodiments herein illustrated and described merely showing some of the various

forms and modifications in which the invention might be embodied.

On the drawing, in which the same reference characters refer to the same parts throughout, and in which are disclosed preferred embodiments:

Figure 1 is a view in perspective of my invention as applied to a vanity bag illustrating it in its closed position;

Figure 2 is an enlarged sectional view taken on the line 2—2 of Figure 1;

Figure 3 is a view in perspective of one of the closure fasteners;

Figure 4 is a sectional view substantially similar to Figure 2 but showing another embodiment of my invention, and

Figure 5 is a plan view somewhat diagrammatic illustrating a band or strip of metal and showing one method of forming my improved closure fastener device.

My invention, in the forms or embodiments shown in the drawing and briefly described, comprises a vanity bag 10, closure members indicated generally as at 12 which are connected together by means of a string or other flexible medium 14. The fabric or flexible material comprising the bag or other construction to which the closure members are fastened is formed with a pair of vertically extending and elongated beads 16. These beads are preferably formed by encircling the fabric about a suitable stiffening material indicated at 15 and stitched as indicated at 17 for retaining the bead in its elongated form.

Referring particularly to the embodiment of my invention illustrated in Figures 2, 3 and 5, each of the metallic retainer members 12 is formed so as to provide a pair of integrally connected vertically extending hook shaped members arranged back to back. Each hook shaped member comprises a vertically extending flat body portion 18 constituting the back thereof and a pair of laterally and outwardly extending upper and lower bent portions 19 projecting from the upper and lower extremities of the body portion 18. The upper and lower bent portions 19 also include end portions or sections 20 preferably bent so as to substantially parallel the body portion 18. It will be noted with particular reference to Figures 2 and 3 that the upper and lower pairs of end portions 20 are in alignment, of the same substantially vertical length and provide a space between their extreme ends indicated as at 21, for a purpose to be readily understood.

Referring now particularly to Figure 5 it will be noted that small openings 22 are formed at

20

the terminal of the lower split lines 23, whereas indentures 24 are provided at the extreme lower end of the upper line of division 23. These indentures 24 extend on both sides of the lines of division 23 for permitting the formation of the return bend indicated at 18' with the minimum danger of breaking at this point, and at the same time preventing the outer surface of the return bend portion against projecting beyond the adjacent edge of the fastening device when in its formed position. This construction, it will be readily appreciated, permits the formation of these fastening devices without the least waste of material. The semi-circular openings 22 provided in the lower outer edges of the fastening devices, as clearly shown in Figure 5, are formed for the purpose of assisting the fastening and location of the flexible string 14. This novel structure is preferably best shown in Figure 3 wherein it will be obvious that the flexible string 14 will be confined between the adjacent semi-circular recesses 22-22'. In manufacturing or forming these clips horizontally or as illustrated in Figure 5, the lines of severance of these clips from its horizontally extending strip 30 is shown at 23', whereas the lines of division 23 extend but partially through the blanks for the fastening devices. It will be appreciated, of course, that should these clips be stamped from a relative narrow strip or vertically with respect to one another, a strip merely the width of the blank shown at 31 is required.

Referring now with particular reference to Figure 4 of the accompanying drawing, it will be noted that the upper looped portion 19 is constructed similarly to the embodiment already described but that the parallel end portions 20 in this instance are projected downwardly to a point relatively close to the lower pair of diametrically opposed and outwardly projecting saddle portions 19'. In this form the portions 19' extend laterally from the vertically extending body portion 18 and the free end or extremity thereof extends slightly upwardly. In this instance the places 21 between the extreme ends of the bent portions is relatively close to the bottom thereof.

It will also be observed in Figure 4 that instead of completely wrapping all of the flexible material 16 around the filler pieces 15, these filler pieces 50 are relatively smaller and the stitching 17 separates the enlarged body of the beaded edge from a relatively smaller and rounded auxiliary edge 18'.

In each of these embodiments of my invention a slight space is provided between the outer surface of the elongated beaded edges and the interior surfaces or passageways provided in the closure fasteners for effectually permitting a ready sliding movement without the least danger of separation, wedging or binding and without the least possibility of becoming separated with respect to each other. Then too, by reason of the fact that the vertical flat body portions extend along the substantial height of the retainer members, spaces 65 providing effective passageways for retaining their respective beads are provided. This construction lends itself to many uses and in connection with materials of various weights and thicknesses and for a great variety of purposes depending upon the gauge or thickness of the materials employed.

I claim:

1. A metallic retainer for closing a pair of flexible beaded edges arranged lengthwise with respect to each other, comprising a pair of members,

each having a vertically extending flat body portion, the inner opposing surfaces of said members disposed in closely contacting position, the upper ends thereof being provided with laterally projecting bent portions disposed in opposite directions with respect to each other, and terminating in downwardly extending and substantially parallel end portions, the lower ends of the flat body members being provided with saddle portions, each being bent outwardly and in opposite directions with respect to one another, and a return-bend portion formed integrally with a pair of adjacent side edges of the flat body members for retaining the contacting surfaces of said body members in a back to back position. 15

2. A metallic retainer for closing a pair of flexible beaded edges arranged lengthwise with respect to each other, comprising a pair of members, each having a vertically extending flat body portion, the inner opposing surfaces of said members disposed in closely contacting position, the upper ends thereof being provided with laterally projecting bent portions disposed in opposite directions with respect to each other, and terminating in downwardly extending and substantially parallel end portions, the lower ends of the flat body members being provided with saddle portions, each being bent outwardly and in opposite directions with respect to one another, the said vertically extending flat body members being further provided with upper and lower indentures formed in the outer edges thereof and a return bend portion formed integrally with a pair of adjacent side edges of the flat body members, said return bend portion extending between the upper and lower indentures and the length thereof being limited by said indentures. 30

3. A metallic retainer for closing a pair of flexible beaded edges arranged lengthwise with respect to each other, comprising a pair of members, each having a vertically extending flat body portion, the upper ends thereof being provided with laterally projecting bent portions disposed in opposite directions with respect to each other, and terminating in downwardly extending and substantially parallel end portions, the lower ends of the flat body member being provided with laterally extending and diametrically opposed bent portions, and terminating in upwardly extending end portions, said upwardly extending end portions being in substantial alignment with the downwardly extending parallel portions, providing passageways therebetween, said passageways being substantially midway between the upper and lower extremities of the end portions and at right angles with respect to said vertically extending flat body members. 50

4. A fastening device for connecting a pair of flexible side walls having beaded edges elongated in cross-section, comprising a metallic retainer consisting of a pair of vertically extending flat body portions arranged in a back to back and closely contacting relation, upper and lower outwardly projecting bent portions formed from said vertically extending flat body portions, and downwardly projecting and substantially parallel end portions providing elongated passages therebetween, both of said passages being vertically disposed and adapted to freely receive said beaded edges, and a return-bend edge integrally formed with both of the vertically extending flat body portions and securely retaining said flat body portions in flat and closely contacting relation. 70

5. A metallic retainer for closing a pair of flexible beaded edges arranged lengthwise with respect to each other, comprising a pair of hook shaped members back to back and in contacting engagement with each other, each having a vertically extending body portion providing the back thereof, the upper ends thereof being provided with laterally projecting bent portions disposed in opposite directions with respect to each other, 10 and terminating in downwardly extending and substantially parallel end portions, the lower ends of the flat body member being provided with laterally extending and diametrically opposed bent portions, and terminating in upwardly ex-

tending end portions, said upwardly extending end portions being in substantial alignment with the downwardly extending parallel portions, providing passageways therebetween, said passageways being substantially midway between the upper and lower extremities of the end portions and at right angles with respect to said vertically extending flat body members, and a return-bend portion formed integrally with a pair of adjacent side edges of the flat body members for retaining the contacting surfaces of said body members in a back-to-back position.
